UNITED STATES PATENT OFFICE

113,360

DESIGN FOR A WARMING CLOSET FOR RANGES

Edwin R. Culver, Jr., St. Louis, Mo.

Application October 8, 1938, Serial No. 80,335

Term of patent 7 years

To all whom it may concern:

Be it known that I, Edwin R. Culver, Jr., a citizen of the United States, residing in the city of St. Louis and State of Missouri, have invented a new, original, and ornamental Design for a Warming Closet for Ranges, of which the following is a specification, reference being had therein to the accompanying drawing.

In the drawing:

The figure is a view in front perspective of the warming closet showing my new design.

I claim:

The ornamental design for a warming closet for ranges, as shown.

EDWIN R. CULVER, JR.
